UNITED STATES PATENT OFFICE.

HENRY P. KRAFT, OF RIDGEWOOD, NEW JERSEY.

DUST-CAP.

1,315,778.

Specification of Letters Patent.

Patented Sept. 9, 1919.

Application filed May 2, 1919. Serial No. 294,265.

To all whom it may concern:

Be it known that I, HENRY P. KRAFT, a citizen of the United States of America, residing in Ridgewood, in the county of Bergen and State of New Jersey, have invented certain new and useful Improvements in Dust-Caps, of which the following is a specification.

This invention relates to dust caps for 10 tire valves or the like and aims to provide certain improvements therein.

As is well known, the function of a dust cap is to inclose the projecting end of the valve of a pneumatic tire for the purpose 15 of excluding dust, mud, etc., and for the purpose of protecting the valve and its cap from shocks or blows, caused by impact with stones or other objects.

Originally such caps were formed of solid 20 metal bored to cap form and provided with a thread adapted to engage the threads of the valve casing. Subsequently they were constructed by drawing deep cups from sheet metal, the open end being contracted 25 and threaded. By this means, the cost of construction was reduced by eliminating waste of metal and long boring and threading operations. Such drawn metal caps have been the standard construction for 30 many years. While such caps show considerable economies over the older type of solid cap, they are nevertheless expensive to manufacture, due principally to the long series of drawing operations.

According to the present invention I provide a dust cap which is efficient in operation, symmetrical in appearance, and exceedingly cheap in cost of construction. By the invention, such drawing operations may 40 be entirely eliminated, thus avoiding the principal cause of expense of the standard construction. The invention also enables the full advantage to be taken of iron or steel as a construction material, which, up 45 to the present, has not been availed of, due to the difficulty of drawing the metal as compared with brass. It has been found in practice that because of the lesser ductility of steel, the drawing operations have been 50 much slower and the wear and tear on the dies has been excessive.

My invention comprises essentially a dust cap formed in longitudinal sections, preferably two in number, which sections are preferably stamped up by a single blow of a 55 stamping press, which not only produces the proper semicylindrical shape, but also trims the blank, leaving but the operation of assembling to produce the complete unthreaded cap. Preferably such sections are 60 united by flanges turned one over the other and preferably also each blank is provided with a rib extending longitudinally of the blank, and spaced midway between the flanges, which rib extends outwardly as a 65 substantial counterpart of the flanges so that the completed cap presents the exterior appearance of a closed cylinder having four external ribs. Instead of being detrimental, these ribs serve the very useful purpose of 70 providing a secure hand-hold (or tool-hold), by means of which the cap may be easily manipulated. Both the flanges and ribs serve as stiffening members to enable the use of much thinner metal. The invention 75 also includes, in its preferred form, a novel construction of threads arranged between the ribs, which will be hereinafter more fully described.

Referring to the drawings, which illustrate several forms of the invention,—

Figure 1 is an elevation of a completed cap;

Fig. 2 is a diametrical section of Fig. 1 on an enlarged scale;

Fig. 3 is a similar section taken at right angles to Fig. 2.

Fig. 4 is a cross-section on the line 4—4 in Fig. 2.

Fig. 5 is a cross-section on the line 5—5 in Fig. 2.

Fig. 6 is an elevation of a somewhat modified form of cap; and

Figs. 7 and 8 are respectively a cross-section and a plan view of a cap of different 95 shape.

Referring first to Figs. 1 to 5, let A indicate the cap as a whole. As shown, it is formed of two semi-cylindrical shells B and C, each provided with a curved end D so 100 that when the shells or sections are united, one end of the cap will be closed. The in-

vention includes means for permanently uniting the sections preferably with a substantially leak-tight joint. This permanent union may be accomplished in several ways, 5 but that preferred is by turning a flange on one section over a complementary flange on the other section. This flange preferably extends entirely around the closed end of the cap and down the sides of the latter to 10 the end, as indicated at E in Fig. 1. Preferably one of the sections, as for instance C, is formed with a wide flange F, and the other section, as B, with a narrow flange G adapted to abut the flange F, the latter then 15 being turned over the top of the flange G, as best shown in Figs. 3 and 4, the in-turned portion being indicated by the letter H.

The flange E constitutes an efficient finger 20 or tool hold in manipulating the cap. It also constitutes a very efficient stiffening member for imparting rigidity to the cap structure, thus permitting the use of lighter metal than would otherwise be feasible. 25 Preferably I introduce into the structure, a plurality of deep ribs J, preferably arranged midway in the section between the sides of the flange E. These ribs extend outwardly and are arranged longitudinally of the cap, 30 preferably being co-extensive with the sides of the flange E. Ordinarily they will be carried on their tops to points close to or meeting the flange. By properly proportioning the flange and ribs very similar, if 35 not identical, exterior form may be secured, so that the cap has the outward appearance of a four-ribbed cap. This not only adds to the symmetrical appearance of the cap and provides additional finger-hold, but also materially assists in stiffening the cap.

In the process of constructing the shells or sections, a stamping press is preferably employed which is adapted at one stroke to cut out a blank from a strip or sheet of 45 metal, and to simultaneously form the ribs J. The flange F of the member C is of course wider than the flange G of the member B and may be cupped upwardly so that the flange G will fit snugly within the flange 50 F. The two parts being assembled, the flange F may be turned down over the flange G by a single stroke of an appropriate press.

In the standard construction of cap, the metal at the bottom or open end of the cap 55 is pressed inwardly and interiorly screw-threaded by a suitable tap, the screw-threaded portion being of short length.

According to the present invention I prefer to form the threads by a pressing operation 60 with simultaneously swages the metal inward and forms the threads. In carrying this into effect I provide a contracting arbor or die which is screw-threaded on its exterior and which is introduced into the open 65 end of the cap. Simultaneously four

screw-threaded dies approach from the exterior and engage the cap between the ribs and flange, pressing the metal inwardly onto the arbor, thus not only contracting the foot of the cap but pressing the metal into the 70 threads of the arbor. The arbor is then collapsed and withdrawn by a longitudinal movement. During this same operation (or by another operation) a flange K is preferably formed on the foot of the cap so as 75 to provide a wider bearing surface than would be secured by the thickness of the metal itself.

In Fig. 6 I have shown a form of cap A' in which there is an enlarged foot portion 80 L which is screw-threaded as hereinabove described. In this case the ribs J are omitted. This form is useful where the cap is designed to engage a bushing screwed upon the valve casing in contradistinction to the 85 engagement with the casing itself.

In Figs. 7 and 8, the construction is similar to that of Figs. 1 to 5, except that the cap is not of round cross-section. Such and other cross-sections, however, are 90 intended to be covered by the claims.

While I have shown and described certain forms of the invention, it will be understood that I do not wish to be limited thereto, as various changes may be made 95 therein without departing from the spirit of the invention.

What I claim is:—

1. A dust cap for tire valves or the like, comprising a plurality of longitudinal sections permanently and rigidly united to constitute a unitary cap structure having a closed outer end and an open inner end, the cap having means for connection with a tire valve or the like.

2. A dust cap for tire valves or the like, comprising a plurality of longitudinal sections permanently and rigidly united from end to end to constitute a unitary cap structure having a closed outer end and an open 110 inner end, the cap having at its lower end thread-engaging means to adapt it for connection with a tire valve or the like.

3. A dust cap for tire valves or the like comprising a plurality of longitudinal sections permanently and rigidly united to constitute a unitary cap structure by inter-engaging flanges formed upon the sections and extending around the closed top of the cap.

4. A dust cap for tire valves or the like, comprising a plurality of longitudinal sections, the sections being permanently united to constitute a unitary cap structure by interengaging flanges formed upon the sections.

5. A dust cap for tire valves or the like comprising a plurality of longitudinal sections, the sections being permanently united to constitute a unitary cap structure by out-

wardly projecting interengaging flanges formed upon the sections.

6. A dust cap for tire valves or the like, comprising a plurality of longitudinal sections, the sections being permanently united to constitute a unitary cap structure by a wide flange formed on one section and a narrow flange formed on the other section, the wide flange being turned over the narrow flange.

7. A dust cap for tire valves or the like, comprising two longitudinal sections, the sections being permanently united to constitute a unitary cap structure, one section having wide flanges and the other narrow flanges, and the wide flanges being turned over to embrace the narrow flanges.

In witness whereof I have hereunto signed my name.

HENRY P. KRAFT.
